UNITED STATES PATENT OFFICE.

ALFRED W. SAUNDERS, OF MOUNT VERNON, NEW YORK, ASSIGNOR TO WESTERN ELECTRIC COMPANY, INCORPORATED, OF NEW YORK, N. Y., A CORPORATION OF NEW YORK.

RADIO SIGNALING SYSTEM.

Application filed July 21, 1925. Serial No. 44,989.

This invention relates to radio signaling systems and more particularly to apparatus for coupling space discharge tubes.

It is usually found, in dealing with high frequency repeaters and amplifiers, that each element reacts upon every other with which it is associated and that it is often difficult to couple one element to another without producing effects whose occurrence is not readily predictable and which are difficult to control. For example, in radio receiving systems employing high frequency amplifiers, it may be possible to use transformers for coupling several space discharge devices in tandem and to secure a transmission characteristic having no serious irregularities. But when it is attempted to couple another element such as a local heterodyne oscillator by means of a coil inductively associated with the transformer for coupling the circuits of the discharge devices, irregularities of a detrimental character are generally introduced. This is because of the mutual reaction between the coupled circuits.

The use of high frequency amplifiers, especially in connection with heterodyne receiving circuits, is desirable because of the advantages which result. Among these advantages are the increased amplification and selectivity which may be obtained, with a consequent reduction of interference from static disturbances and without greatly increased liability of distortion caused by singing or parasitic oscillations. The problem of properly coupling high frequency amplifiers and oscillators with each other and with other portions of their associated circuits is thus seen to be of considerable importance.

It is an object of this invention to inductively couple a source of local waves to a wave transmission path, including high frequency amplifiers, and to maintain a desirable transmission characteristic for the wave transmission path.

A further object is to combine signal waves and local waves in a transmission path and to prevent detrimental effects upon the transmission characteristic of the path.

An additional object is to prevent the radiation of energy from a local oscillator inductively coupled to a circuit including an antenna.

A further object is to simplify the coupling

arrangements for oscillators and amplifiers. 55

A feature of the invention is a transformer designed to couple amplifiers in tandem and to couple the input and output circuits of a space discharge oscillator to each other and to the tandem circuit. 60

A further feature lies in a specific arrangement and design of transformer windings for coupling amplifier, detector and oscillator circuits, whereby a substantially uniform transmission characteristic for the transmission path is secured. 65

The invention comprises broadly, a high frequency circuit including repeaters coupled in tandem and another repeater having input and output circuits coupled for the generation of oscillations, all couplings being effected by a single transformer including a plurality of windings arranged coaxially and so positioned with respect to each other that one repeater may constitute a high frequency 75 amplifier, and is arranged between the oscillator and an antenna, to prevent the radiation of waves generated by the local oscillator. The transformer windings may be of any desired form, for example, annular or co- 80 noidal.

The invention is illustrated in the drawings wherein Fig. 1 shows a general application of the invention to the coupling of repeaters. 85

Fig. 2 is a graph illustrating the transmission characteristic of a circuit including the invention.

Fig. 3 illustrates a radio receiving circuit including the coupling arrangement of the 90 invention.

The invention will first be described with reference to Fig. 1. A space discharge tube 10 which represents, for example, a high frequency amplifier includes the customary electrodes and associated circuits wherein an inductance 11 has a portion included in an input circuit connected to the control electrode and cathode, and a transformer 12 has a primary winding 20 connected to the 100 anode of the tube 10. Condenser 13 balances the inherent capacity of the electrodes of the tube. A secondary winding 14 of transformer 12 is included in a circuit connected to the control electrode of a repeater tube 15 which may be an amplifier or a detector or the like. 105

A third space discharge tube 16 has an

input circuit connected to its control electrode and cathode including another winding 17 of the transformer 12. An adjustable condenser 18 is shown connected in 5 shunt to this winding to form a resonant circuit therewith. An output circuit for tube 16 is connected to its anode and includes the fourth winding 19 of transformer 12. The windings 14, 17, 19 and 20 of transformer 10 12 are all coupled together, thus the windings 17 and 19 couple the input and output circuits of tube 16 to each other and to the tandem arrangement of repeaters 10 and 15, which are in turn coupled by the windings 20 and 14. The 15 resonant element 17—18 determines the frequency of oscillations, generated by the circuit including tube 16, which are produced by virtue of the coupling between its input and output circuits afforded by transformer 12.

20 The winding 17 of transformer 12, which is connected to the grid of tube 16, is positioned adjacent to the winding 14 connected to the control electrode of tube 15 and winding 19 is positioned adjacent the winding 17, 25 whereas winding 20 is positioned adjacent to winding 14. Windings 19 and 20 are therefore remote from each other and the mutual inductance between them is made small so that undesirable reaction of the oscillator on the 30 amplifiers is avoided.

The inductance 11 may represent an antenna such as a loop antenna and by interposing the uni-laterally conducting tube 10 between the antenna and the oscillator 16 the radiation 35 of waves produced by the oscillator from the antenna is prevented. It is to be understood that the inductance 11 may be coupled to an ordinary open antenna.

A specific form of transformer which was 40 found to function without introducing undesired irregularities in the transmission characteristic of the associated circuit consisted of windings of annular shape having an outside diameter of two inches, an inside diameter of one inch and a thickness of $3/64$ inches. Windings corresponding to windings 20 and 45 14 of Fig. 1, included approximately 170 and 190 turns, respectively, and were spaced with their adjacent sides $5/36$ inches apart. Windings 50 corresponding to 17 and 19 of Fig. 1 included approximately 70 and 50 turns, respectively, and were spaced with their adjacent sides $1/8$ inches apart.

By this arrangement the coupling circuit 55 is simplified since in the ordinary case a separate transformer or at least separate windings would be required for coupling the oscillator to the input circuit of tube 15. The extra transformer or windings are hereby 60 eliminated without detriment to the transmission characteristic of the circuit.

The approximate transmission characteristic obtained by using a coupling arrangement, substantially as described above, is represented 65 by curve A of Fig. 2. This relatively

smooth transmission characteristic was secured by the design and arrangement of the transformer windings and the advantage of the particular design specified is clearly brought out by reference to curve B of Fig. 70 2 which illustrates the transmission characteristic of substantially the same circuit with a different arrangement of transformer windings. The curve A represent a transmission characteristic free of serious irregularities, i. e. substantially uniform for a 75 definite frequency range, whereas the curve B represents a characteristic containing irregularities which would produce serious distortion. 80

The radio receiving circuit illustrated in Fig. 3 is of the heterodyne type and includes an antenna 25 and an associated tuning condenser 26 connected to electrodes of a space discharge tube 27 designed to amplify high 85 frequency waves.

The mid-point of the loop 25 is connected to the cathode of tube 27 in series with the filament of detector tube 28. One outer terminal is connected to the control electrode of tube 27 and the other outer terminal is connected by the path including condenser 29 to the anode of tube 27. Condenser 29 functions in a manner generally understood to 90 compensate for inherent capacity between the grid and anode of tube 27, so that the production of parasitic oscillations in the amplifier circuit is prevented.

A space current circuit for tube 27 includes the winding 20 of transformer 12, one terminal being connected to the anode and the other connected to space current source represented by battery 30, thence to ground at the cathode of tube 27. This circuit also constitutes the alternating current output circuit of tube 27 which is coupled to the input circuit of detector 28 by the winding 14 having one terminal connected to the control electrode and the opposite terminal connected to the cathode of tube 28 in series with the filaments of tubes 33, 35, 34, 32, and 31. 100

An oscillator includes tube 35, the winding 17 of transformer 12 connected between its control electrode and cathode and the winding 19 connected between its anode and cathode; the two windings serving as a feedback coupling for the generation of oscillations. An adjustable condenser 36 is arranged in shunt to winding 17 to provide a resonant circuit for determining the frequency of oscillations generated by the system including tube 35. The space current circuit of tube 35, connected to its anode and cathode, includes the winding 19 of transformer 12 in series with space current source 30. 110

The transformer 12 in this figure has its circuit coupled in the manner illustrated and described in Fig. 1 and functions to provide a desirable transmission characteristic in the manner described in connection with Fig. 1. 120 130

The detector tube 28 has its output circuit coupled to a two stage intermediate frequency amplifier 40 including space discharge tubes 31 and 32 and associated circuits which will not be described in detail, since these elements form no material part of the invention. They accordingly may be arranged in any well known manner.

A second detector tube 33, including the well known arrangement of grid leak resistance and blocking condenser 41 in its input circuit, has this circuit coupled to the output circuit of intermediate frequency amplifier 40. The output circuit of detector 33 is coupled to the input circuit of an audible frequency amplifier 34. The amplifier 34 includes terminals 42 adapted to be connected to a suitable receiving device, wire line or the like.

20 In the operation of the circuits shown in Fig. 3, high frequency waves modulated in accordance with signals are received by antenna 25 and are supplied to the input circuit of tube 27. The received waves are amplified by tube 27 and supplied through windings 20 and 14 of transformer 12 to the input circuit of detector 28.

Oscillations are generated in the circuits associated with tube 35 by virtue of the coupling between coils 17 and 19 as already mentioned. These oscillations are supplied to the input circuit of detector 28 by virtue of the coupling between coils 14 and 17.

The received waves and local oscillations are supplied to the input circuit of the detector 28 in which they are combined to produce, in the output circuit, signal modulated waves of an intermediate frequency, which is preferably above the range of audibility. However, the frequency of these waves should be sufficiently low to be readily amplified by the intermediate frequency amplifier 40. The amplified intermediate frequency waves are detected, in the device 33, in the manner well understood and then amplified by device 34 and supplied to the device or line connected to terminals 42.

This invention has been described in association with certain specific embodiments for the purpose of more clearly explaining the principles of its operation and not for the purpose of defining its scope which it is understood is determined only by the appended claims.

35 What is claimed is:

1. In combination, an antenna, a high frequency amplifier, a detector and an oscillator, each having an input circuit and an output circuit, means for connecting the input cir-

cuit of the amplifier to the antenna, and a 60 transformer having windings inductively associated for coupling the output circuit of said amplifier to the input circuit of said detector, for coupling the input and output circuits of said oscillator and also for coupling said oscillator to said detector.

2. In a radio system comprising an antenna, space discharge tubes, an input circuit and an output circuit associated with each tube, a transformer having inductively associated 70 windings for transferring energy from the output circuit of one tube to the input circuit of a second tube, between the input and output circuits of a third tube to constitute an oscillator and to the input circuit of said 75 second tube from the oscillator, whereby oscillations may be supplied to the input circuit of the second tube but are substantially prevented from reaching the antenna.

3. In a radio system, space discharge tubes, 80 each having input and output electrodes, input and output circuits for each tube, and a transformer having four annularly and coaxially positioned windings respectively included in the output circuit of the first tube, 85 the input circuit of a second tube, and the input and output circuits of a third tube, said second winding separating said first winding from the other two windings.

4. In a radio receiving system, a high frequency amplifier, a high frequency detector, and a high frequency oscillator, said amplifier, detector and oscillator including respective input and output circuits, and a transformer having inductively associated windings connected respectively in the output circuit of the amplifier, in the input circuit of the detector, and inductively associated windings connected respectively in the input and output circuits of said oscillator, said oscillator 100 windings being adapted to couple said oscillator to said detector input circuit and being separated from said first winding by said second winding.

5. In a radio receiving system, an oscillator, 105 an amplifier and a detector, each having input and output circuits, an incoming circuit and a transformer having inductively associated windings connected respectively in said incoming circuit, in the input circuit of said 110 amplifier and in the input and output circuits of said oscillator, the winding in the output circuit of said oscillator being separated from the winding in the incoming circuit by said other two windings.

In witness whereof, I hereunto subscribe my name this 17th day of July, A. D. 1925.

ALFRED W. SAUNDERS.
